UNITED STATES PATENT OFFICE

155,086

DESIGN FOR A TOY FOWL

Adolph Goldfarb, Chicago, Ill.

Application July 7, 1949, Serial No. 3,764

Term of patent 14 years

(Cl. D34—15)

To all whom it may concern:

Be it known that I, Adolph Goldfarb, a citizen of the United States, residing at Chicago, county of Cook, and State of Illinois, have invented a new, original, and ornamental Design for a Toy Fowl, of which the following is a specification, reference being had to the accompanying drawing, forming a part thereof.

Fig. 1 is a side view of a toy fowl showing my new design.

Fig. 2 is a front view thereof.

Fig. 3 is a front view showing the toy fowl in a depressed position, and

Fig. 4 is a bottom view.

I claim:

The ornamental design for a toy fowl, as shown.

ADOLPH GOLDFARB.
